VAPORIZING DEVICE

Filed Nov. 10, 1930

Fig. 1.

UNITED STATES PATENT OFFICE

ABRAHAM J. LICHTIG, OF OAKLAND, CALIFORNIA

VAPORIZING DEVICE

Application filed November 10, 1930. Serial No. 494,585.

My invention relates to devices for emitting vaporous exhalations for any purpose for which fumigants are used, whether such exhalation be offensive or noxious, stifling or irritating or merely odorous as, for example, a perfume vapor.

Though my invention in its concrete or structural form extends to and includes any and all of the numerous uses of which it is capable, its particular object for which it is, at present, intended, is as a fumigant against moths, it being to this end especially adapted for closets and other small, closed chambers in which clothes or fabrics are stored.

Briefly stated, my invention comprises a container adapted for convenient suspension in a closet, said housing or shell having fitted within it a vial containing a vapor-exhaling or volatile substance, in this case, cedar oil, for example. From this oil leads a wick, by the capillary attraction of which the oil is raised and allowed to volatilize as vapor which escapes, through openings in the container, into the closet. Means are provided for arresting the function of the wick when the device is not in use, and for conveniently restoring said function when vaporization is desired.

In the accompanying drawing to which reference is made, I have shown my device in its preferred form, though it is to be understood that changes may be made therein without departing from the spirit of the invention as defined by the claims hereunto appended.

In the drawing Fig. 1 is a vertical sectional elevation of my vaporizing device.

Fig. 2 is a section on the line 2—2 of Fig. 1.

1 is a housing or shell; in practice, for example, a card-board carton, having openings 2 in its walls near its upper end, and provided with a securely fitting cap 3. Within the carton is fitted a block 4, preferably of wood, having a socket 5 in its axis opening downwardly from its top. In this socket is rigidly fixed, by means of suitable adherent, a bottle or vial 6 with a stopper 7 in its mouth.

In the vial is the vapor-emitting substance

indicated by 8, which substance, as I have hereinabove stated is, or may be, for the use intended, cedar-oil.

9 is a wick which, preferably, comprises several flat strips side by side, making a relatively wide capacious capillary conveyer. The lower end of the wick dips into the oil 8, and thence rises between the stopper 7 and the vial neck, and hangs its upper end over said neck as shown at 9', to an extent sufficient to prevent it from dropping into the vial when the stopper is loosened.

10 is a pressure-resistant member in the form of a yoke or stirrup freely straddling the projecting upper end of the vial and its stopper, the top of said yoke bearing under a shield disk 11 lying between said top and the cap 3 of the carton, and its foot-extremities being firmly seated in the top of the block 4.

12 is an externally threaded post or stud passing freely through the carton cap 3, shield disk 11 and the top of the yoke 10. It is provided with a flange 13 which bears upon the top of the stopper 7. Below this flange the stud 12 is threaded as a wood screw 14 which penetrates the stopper and is preferably cemented thereto for fixed engagement therewith, while above said flange it is threaded as a machine screw 15, which is fitted with a nut 16, bearing upon the carton cap 3, and carrying a suspension ring 17.

To charge the device, and prepare it for use, the vial 6 having been exposed and opened by the removal of the upper members including the stopper, or, for that matter, by the removal and disassembling of all the interior parts, block, vial and all, from the carton, the volatile substance 8 is supplied. Then the wick 9 is dipped in said substance and carried up to hang over the bottle rim at 9'. The stopper 7 is thereupon fitted in the neck of the vial with pressure sufficient not only to close said neck, but also to compress the wick against the neck wall with such tightness that the capillary function of said wick is practically destroyed and any seepage therethrough prevented. Then the yoke 10, the shield disk 11 and the carton cap 3 are replaced, the threaded lower end 14 of the

stud 12 having been previously screwed into the stopper 7 until the flange 13 of the stud bears upon top of said stopper. The nut 16 is then fitted to the upper end 15 of the stud and turned down lightly upon the carton cap 3. The device is now hermetically sealed for transportation and storage. When ready for use, the nut 16 is turned down with increasing tightness until, due to the resistance it meets 10 with in the yoke 10 and block 4, it raises the stud 12, and thereby lifts the stopper 7, relieving the pressure upon the wick 9, thereby restoring the capillary function of said wick and allowing the oil 8 to seep up through the wick and be volatilized at the wick end 9' and pass out as vapor from the carton 1 through its holes 2. Then the device is hung up by the ring 17 in the closet or other chamber which it is desired to fumigate. The 15 shield disk 11 is a guard for the carton cap against undue deterioration from the escaping vapor.

In order to shut off the operation of the device, and restore it to non-use, the nut 16 is turned upwardly upon the stud 12, and the latter is then manually pressed down to again tighten the stopper in the vial.

When the device is in use, and hanging from the ring 17, its weight is carried by the 20 nut 16 and stud 12, the flange 13 of said stud bearing against the bottom of the yoke 10 and through it against the bottom of the cap 3. Said cap fits the carton 1 tightly, and may, if desired, be provided with any ordinary 25 means for holding it thereupon, so that the weight of the carton, block, and vial can be suspended from it. The extent of movement of the stopper 7, before the flange 13 strike the bottom of the yoke 10, is sufficient to relieve the pressure upon the wick without 30 freeing it so completely that it might drop down into the vial.

I claim:—

1. A vaporizing device comprising an ap- 45 ertured shell; a block fitted therein; a vial for a volatile substance carried by said block; a wick dipping into the volatile substance and hanging over the mouth of the vial for exposing the seeping substance to evaporation; a stopper in the vial neck adapted by pressure upon the wick to control its capillary function; and means for withdrawing the stopper to relieve its pressure upon the wick consisting of an axially movable flanged 50 stud associated with the stopper; a nut threaded upon said stud for moving it; and a pressure resisting yoke carried by the block and bearing under said nut.

2. A vaporizing device comprising an ap- 60 ertured shell; a block fitted therein; a vial for a volatile substance carried by said block; a wick dipping into the volatile substance and hanging over the mouth of the vial for exposing the seeping substance to evaporation; a stopper in the vial neck adapted by 65

pressure upon the wick to control its capillary function; and means for withdrawing the stopper to relieve its pressure upon the wick consisting of an axially movable flanged stud associated with the stopper; a nut threaded upon said stud for moving it; and a pressure resisting yoke carried by the block and bearing under said nut; and a shield disk lying between the yoke and nut. 70

3. A vaporizing device comprising a vial for containing a volatile substance; a holder for said vial; a wick dipping into the volatile substance and extending through the mouth of the vial; a stopper in the vial neck adapted by pressure upon the wick to control its capillary function; and means for withdrawing said stopper to relieve its pressure upon the wick comprising an axially movable stud connected with said stopper, a nut threaded upon said stud for moving it, and a pressure resisting yoke straddling 80 said stopper and resting upon the vial holder, said yoke bearing under said nut. 85

4. A vaporizing device comprising a vial for containing a volatile substance; a holder for said vial; a wick dipping into the volatile substance and extending through the mouth of the vial; a plug in the neck of the vial adapted both to seal said neck and to compress said wick to prevent its capillary function; and means carried by the holder for withdrawing said plug to relieve its pressure upon the wick. 90

In testimony whereof I have signed my name to this specification. 100
